UNITED STATES PATENT OFFICE.

JAMES E. HOMANS, OF NEW YORK, N. Y.

APPARATUS FOR AND METHOD OF TRANSMITTING PHOTOGRAPHS AND OTHER PICTURES TELEGRAPHICALLY.

1,356,767.

Specification of Letters Patent. Patented Oct. 26, 1920.

Application filed June 4, 1915. Serial No. 32,090.

To all whom it may concern:

Be it known that I, JAMES E. HOMANS, a citizen of the United States, residing at New York city, in the county and State of New York, have made a certain new and useful invention in Apparatus for and Methods of Transmitting Photographs and other Pictures Telegraphically.

The object of the invention is to provide an apparatus and method which is simple in construction and arrangement, and efficient and reliable in operation, for telegraphically transmitting photographs, prints, pictures, or the like.

15 A further object of the invention is to provide an apparatus and method of the nature referred to, wherein provision is made to transmit telegraphically not only the maximum and minimum contrasts of colors 20 of a photograph, picture or the like, but also the intermediate shades or colors thereof.

A further object of the invention is to provide a system of the nature referred to capable of being operated over ordinary 25 service telegraph lines, employing the ordinary line batteries or other current sources, utilizing simple current impulses without reversals of the polarity thereof, and without involving any changes in the usual telegraph line arrangements other than attaching the instruments to the line circuit terminals.

Other objects of the invention will appear more fully hereinafter.

35 The invention consists substantially in the construction, combination, location and relative arrangement of parts and mode of operation all as will be more fully herein-after set forth, as shown in the accompanying drawings, and finally pointed out in the appended claims.

Referring to the accompanying drawings:—

Figure 1 is a view in diagram showing 45 certain parts of an apparatus employed either for transmitting or receiving, and also portions of a synchronizing arrangement, and circuit connections embodying the principles of my invention.

50 Fig. 2 is a similar view showing a stylus arrangement adapted for use in securing the desired current pulsations to be sent to the line wire in accordance with my invention.

Fig. 3 is a similar view showing an arrangement and relation of relays for controlling the line impulses, and which, in turn are controlled by circuit connections effected by the operation of the stylus arrangement shown in Fig. 2.

Fig. 4 is a similar view showing the relay system of Fig. 3 with the additional circuit connections required to govern and control the current impulses sent to the line to produce the "dots" and "dashes" and the 65 relation thereof, for efficient transmission of the maximum and minimum as well as the intermediate contrasts of colors or shades of the photograph or other picture to be sent.

Fig. 5 is a similar view showing parts and 70 circuit connections employed in connection with the receiver.

Fig. 6 is a view in diagram illustrating the operation of a graduated shutter adapted for use, in one form of embodiment of 75 my invention, in connection with the receiver.

Figs. 7 and 8 are detail views showing 80 certain parts employed in connection with the synchronizing apparatus employed in connection with my invention.

The same part is designated by the same reference character wherever it appears throughout the several views.

In the efforts heretofore made to transmit 85 photographs, prints, pictures of the like having variations of shades or colors, telegraphically, successful and satisfactory results have been materially and substantially prescribed by reason of the fact that multitudinous and complicated combinations and groups of impulses are required which involve the use of complicated circuit connections and delicate adjustments. Most of the former systems, moreover are exceedingly 95 slow in operation, and where current impulses are employed the excessively large number of impulses required invite derangement due to static or other interference in the line, and, where current fluctuations are 100 employed the operation of line relays is impossible, hence requiring special telephonic or metallic circuits, which materially reduces the universal or extensive use of such systems, and the distance through which transmission may be accomplished.

In the systems heretofore attempted it has also been impossible to secure efficient

transmission over telegraph lines of the intermediate "colors" or shades of a photograph or picture thereby preventing accurate reproduction of the transmitted pictures, particularly in the case of photographs. This failure of the prior systems with which I am familiar to efficiently transmit the intermediate "colors" or shades of pictures, is due to the absence in such 10 systems of means for securing and maintaining the proper transmitted impulses corresponding to the several shades which go to make up the picture.

It is among the special purposes of my 15 invention to provide a system of telegraphic transmission of pictures, prints, photographs or the like, and apparatus therefor, which is simple in construction, arrangement and operation, and wherein the transmission of the pictures, prints, photographs or the like, in the essential variations of "colors" or shades thereof, is successfully and practically accomplished without the necessity of employing multitudinous impulses, or complicated combinations or groups of such impulses, without employing complicated circuit connections or arrangements or delicate adjustments wherein rapid transmission is effected with decreased 25 danger of static interference on the line.

In carrying out my invention, and in the arrangement hereinafter described as an illustrative embodiment of means and methods to accomplish my objects and purposes, I propose to send current impulses over the line of such character as to effect the proper operation of line relays or transfer devices whereby I am enabled to employ the ordinary commercial grounded telegraph 35 wires in the transmission of pictures, prints, photographs or the like, thereby materially increasing the extent of use of the system and also the distance of transmission, and avoiding the necessity of working over 40 special line circuits such as telephonic or metallic circuit lines.

I also propose to employ means to secure and maintain the proper succession or time sequence of the transmitted impulses corresponding to the various "colors" or shades occurring in a picture or photograph. Thus, in accordance with my invention, I propose to provide means and methods to send the proper impulses to line to telegraphically transmit, for example, the maximum dark of a picture, and to follow such impulses in sequential order with other impulses for transmitting successively the dark gray, the light gray and, finally the 50 maximum light, the intermediate "colors" or shades, dark gray and light gray, between the maximum dark and maximum light, being ordinarily sufficient for all practical purposes. The fixed order or sequence above stated, as an example and by

way of illustration, is always maintained whether followed in positive or in reverse direction.

I also propose, in accordance with the principles of my invention, to secure and 70 maintain suitable and proper synchronism of the transmitting and receiving devices, as an essential feature for successfully accomplishing the telegraphic transmission of pictures, photographs or the like. 75

Other special features of my invention will be more fully hereinafter set forth.

The accompanying drawings show essential details and circuit arrangements reduced to a simple form, for illustrative purposes, although it will be readily understood by persons skilled in the art that in practical use and operation many details not necessary here to show or describe, will be employed. 80

Referring to Fig. 1, I have shown at A, a cylinder detachably connected to for ready removal from a hollow shaft A'. This shaft is interiorly threaded to receive a screw threaded spindle A², which is fixed in a 90 suitable stationary support indicated at A³. By rotating shaft A' it is caused to progress along the spindle A², after the manner of a nut traveling along a screw shaft. Rotation may be imparted to the shaft A', in 95 any suitable manner and at a suitably regulated speed in synchronism with other parts of the apparatus or system. In the form shown a gear A⁴ is mounted on shaft A' to rotate therewith but held against movement 100 in such manner that the shaft A' is rotated when the gear A⁴ is driven, and is also moved longitudinally through the hub of said gear. A feather or spline in the hub of gear A⁴ working in a longitudinal groove 105 or slot A⁵ in shaft A', permits this operation. A gear A⁶ mounted on a shaft A¹⁰, meshes with and, when driven, drives gear A⁴. The gear A⁶ is frictionally driven from shaft A⁸, by means of a friction plate A⁷, 110 carried by and rotating with shaft A⁸, and yieldingly pressed against the gear A⁶, as for instance, by means of a spring A¹¹, interposed between said plate A⁷ and an adjusting nut A¹², tapped upon a threaded 115 portion of said shaft A⁸. The shaft A⁸, may be driven in any suitable or convenient manner, as, for instance, by intermeshing worm gears A⁹, from any convenient source. 120

The apparatus so far described is the same 125 whether for transmitting or for receiving, the only differences in arrangement when used for the one purpose or the other being the substitution of a suitable camera shutter controlling device for the cylinder A at the receiving station, and the arrangement of synchronizing devices. It is also to be understood that inasmuch as the cylinder A is designed to support or carry the photograph, print, picture or the like which is to be 130

reproduced at the distant receiving station, or, if not the picture itself, then a cast negative, or other, form of the picture suitable for use in controlling by the colors or shades of the picture the proper impulses to be sent to the line, and required for reproducing or duplicating the corresponding colors or shades at the distant receiving end of the line, therefore the specific form of the holder 5 will vary according to the particular form in which the picture to be transmitted is to be employed at the transmitting end. I shall refer to the form of picture employed at the transmitting station to control the 10 line impulses, as the "original" and whether it be a photograph, print, or other form of picture. This original, as above indicated, may be of any desired form, such, for instance, as a transparency designed to be rotated between a beam of light and a selenium cell, in order to control the impulses sent to line. In the particular form shown as illustrating the principles of my invention I employ an original in the form of a bichromate 15 gelatin relief. This relief may be of any desired or suitable shape. I have shown it, for illustrative purposes, in the form of a cylinder, 10, see Fig. 2, and applied to the exterior surface of the holder A. By making the 20 holder A detachable from its operating shaft A', therefore, I am enabled to substitute any desired form of holder as determined by the character of original employed. 25 In the practical operation of apparatus of the nature to which my invention relates, it is necessary to provide suitable means to secure synchronism of the transmitting and receiving apparatus. That is to say it is 30 necessary to provide means whereby an impulse sent to the line as a result of the control thereover of a given point in the operation of the "original" holder A shall be registered at precisely the same point on the corresponding holder or device at the receiving 35 station. To accomplish this result various arrangements may be employed. As illustrative of a simple arrangement for accomplishing the desired results, I provide means 40 for arresting the rotation of the shaft A', at the receiving station at the end of each complete rotation thereof, and releasing the same again by an impulse sent over the line when the corresponding shaft at the transmitting 45 station is in precisely the same position in its rotative movement. This arrest of the shaft A', may be easily accomplished, if required to secure synchronism, where, as shown, said shaft is driven through the friction drive means A⁷, A¹¹, A¹², above described. The stop device shown for accomplishing the synchronizing action referred to, and as illustrative of the principles involved, consists of a disk or collar T, carried by preferably insulated from shaft A¹⁰, 50 and having a cam projection T', thereon, see Fig. 8. This projection, at the proper point in the rotation of shaft A¹⁰, engages a spring contact T², which normally is closed upon the terminal T³, and pushes the same out of contact, with said terminal. This action occurs each time the shaft A¹⁰, or A', approaches the end of a complete revolution. At the end of the complete revolution of said shafts the spring contact T² is carried into 55 contact with terminal T⁴. When contact spring T² leaves terminal T³, the battery circuit which is controlled by the relay magnet D, is opened at T³. This circuit may be traced from battery X as follows: 60 through wire 11, contact spring T², terminal T³, wire 12, terminal D', armature D² (when relay magnet D is energized) to line wire L'. When contact spring T² is moved into contact with terminal T⁴, the synchronizing 65 or release impulse is sent over the line wire, assuming that switch Q has been moved into contact with terminal Q', and the switch Q³ has also been moved into contact with terminal Q⁵, the circuit at the transmitting 70 station being traced as follows:—from battery X, wire 11, spring T², terminal T⁴, wire 13, switch Q, terminal Q', line wire L', returning from the distant receiving station through opposite lead or ground L², switch Q³, terminal Q⁵, wire 14 to the other side of the battery X. The switches Q, Q³, should be moved into the respective positions thereof as above stated when the apparatus is in operation for transmission. At 75 the same time, or when the apparatus is in operation for transmission the stop device K', which co-operates with the stop K fastened to shaft A¹⁰, see Fig. 7, should also be moved back out of engagement with the 80 stop K. When the apparatus is to be used for receiving the switches Q and Q³, should be moved into position to contact, respectively, with terminals Q², Q⁴, and the catch device 85 K' should be in engagement with the stop K, at the proper point in the rotation of shaft A¹⁰. This point corresponds to the neutral and starting position of the parts at 90 both the transmitting and receiving stations with the shaft A¹⁰, or A', having just completed a revolution and not yet commenced another. 95 Assuming the parts to be arranged for receiving, impulses are sent to the line wire L', at the distant transmitting station by the proper energization of the relay magnet D at that station, as will be more fully hereinafter explained. At the receiving station the impulses come in over the line wire L', 100 and effect the energization of polarized relay R, through wire 21, wire 22, contact Q⁴, switch Q⁵, to ground or return L², thereby closing armature R¹⁰, against terminal R'. Thereupon an impulse circuit at the receiv- 105

ing station is closed as follows: from the right hand pole or battery X, through wire 14, wire 15, armature R¹⁰, terminal R', wire 16, wire 17, to the receiving relays, presently to be described, and back through wire 18, terminal S⁵, armature S⁶, wire 19, and wire 20 to the other pole of battery X. At the instant of synchronism, which should be as nearly simultaneous as possible at both the 10 transmitting and receiving ends although in practice the receiving shaft might be adjusted to revolve slightly faster than the corresponding shaft at the transmitter, the contact between spring T², and terminal T⁴ 15 is made, as above explained, thereby closing the following circuit from the battery X, namely, through wire 14, wire 15, wire 23, magnet S, wire 24, contact Q², switch Q, wire 13, terminal T⁴, spring T², and wire 11 20 back to battery X. The resulting energization of magnet S, attracts its armature S², thereby completing circuit between armature S² and terminal S', and at the same time ringing bell S¹⁰. The contact of armature S² with terminal S', completes the 25 following circuit: from battery X, through wire 14, wire 25, magnet S³, wire 26, terminal S', armature S², wire 27, wire 20, to the other side of the battery X. The completion 30 of this circuit energizes magnet S³, thereby attracting its armature S⁶, breaking contact with terminal S⁵, and making contact with terminal S⁴. Since the rotation 35 of shaft A¹⁰, at the receiving station has been arrested by the catch K', engaging the stop K, the apparatus is ready to receive the synchronizing impulse which is to be sent over the line from the distant transmitting station. When this impulse arrives at 40 the receiving station it again energizes relay R, and attracts its armature R¹⁰, against terminal R', thereby closing the following circuit: from battery X, through wire 14, wire 15, armature R¹⁰, terminal R', wire 16, 45 wire 28, magnet K², wire 29, magnet S⁷, wire 30, terminal S⁴, armature S⁶, wire 19, wire 20, to the other side of the battery. The completion 50 of this circuit not only energizes magnet K², thereby releasing the catch K' from stop K, and permitting the further rotation of shafts A¹⁰ and A', but it also causes bell S¹¹ to sound through the striking thereagainst of the clapper on the armature S⁸ of magnet S⁷, which magnet is energized by the closing of the same circuit. 55 The time interval between the sounding of the two bells indicates the closeness of the synchronism, and this time interval may be adjusted to the required or desired extent. 60 The two signals should be adjusted to follow each other in very close succession if the proper synchronism is observed, so that the arrest of shaft A¹⁰ is scarcely perceptible.

While the double signal is not necessary, 65 and one or both may be omitted, or the mag-

net S may be dispensed with and its associated bell S¹⁰, controlled by the armature S⁶, of magnet S³, the arrangement as shown is simple and illustrates the principles of my invention.

I will now describe the arrangement at the transmitting station for sending the required impulses to line, it being remembered that the basic principle involved consists in securing and maintaining a time sequence of transmitted impulses corresponding to the several shades or colors of the picture to be transmitted. That is, in the operation of transmitting a picture successfully and in accordance with my invention 75 as above explained, the colors or shades of the picture should be transmitted in fixed sequential order, from the maximum dark to the maximum light, or vice versa, through the intermediate stages of color or shade. 80 Thus if a "black" immediately succeeds a "white" on the photograph to be transmitted, the impulses corresponding to the intermediate colors or shades of "light gray" and "dark gray," must be sent over the line 85 after the "white" and before the "black" impulse is sent. By observing this fixed sequence of transmission of impulses I am enabled to avoid seriously complicated impulse-combinations while securing a transmission of a sufficient range of colors or 90 shades for all practical purposes.

The desired sequential or successive order of impulses may be secured in many different ways and by various arrangements, dependent upon the particular character of "original" of the picture to be transmitted. Where a bichromate photo-relief is employed, as in the case which I have selected 100 for illustrative purposes, the desired result 105 is easily attained by means of stylus operating over the surface of the relief "original," and the movements of the stylus employed to control suitable circuit connections. In this case a film of gelatin, 110 sensitized with potassium bichromate is exposed to light under a photographic negative, the portions of the photograph which are light (dark on the negative) protect the bichromate film from the action of the light 115 rays, and hence the surface of the film covered by said portions will not be affected. On the other hand, the portions of the photograph which are dark, (light on the negative) will allow the light to penetrate 120 to the surface of the sensitized film and exert a maximum effect thereon. The intermediate shades or "colors" of the photographic negative will, of course, correspondingly affect the surface of the sensitized film, 125 according to the degree of light permitted by them to penetrate to the film. After the exposure of such a film under a photograph, the film is immersed in a bath of cold water with the result that the portions of the sur- 130

face thereof which have not been affected by the light of the exposure will swell to the greatest height, while those which have received the maximum effect of the light will 5 not swell, and the portions of the film surface which were under the intermediate shades of the photograph will swell to an extent dependent upon the degree of light permitted by the negative to penetrate to 10 the film surface. There is thus produced a surface in cameo-relief in which the areas corresponding to the whitest or lightest portions of the photograph are elevated to the greatest extent, and the areas corresponding 15 to the darkest portions of the photograph are not elevated or raised at all, while the areas corresponding to the intermediate shades are elevated to an extent dependent upon the degree of light or dark in the 20 corresponding portions of the photograph. Now, by suitably operating a stylus over this film surface, so prepared, a movement of the stylus is secured as it follows the irregular cameo surface of the film, and 25 these movements of the stylus are utilized to suitably control electric circuits for sending the required impulses to line, such control in accordance with my invention, consisting in making or breaking the necessary 30 and corresponding circuit connections to make or break the circuits. In other words I employ the cameo surface to accomplish the necessary successive or sequential closing 35 of relay circuits.

It is obvious that the cameo-film may be employed in any desired form for coaction therewith of the stylus which controls the circuit contacts or connections. As illustrative of one form of operative embodiment of my invention the cameo-film 10 is applied to or wound upon the exterior surface of the cylinder A at the transmitting station. This cylinder, constituting a 40 holder, as above explained, is not only rotated but is simultaneously moved endwise by reason of its connection with shaft A' and the connection of the latter with the screw spindle A². The arrow in Fig. 2 indicates the direction of rotation of the cylinder A.

Bearing against the cameo relief film 10, is a stylus B, which is carried and yieldingly impelled endwise into contact with the film 10 in any suitable manner, as, for 45 instance, by the spring or equivalent member B', secured in any suitable way to any convenient fixed point indicated at B², and thus is enabled to follow the variations in heights and depths of the cameo relief surface of the film in a path around and around the circumference of the cylinder as the latter rotates and progresses longitudinally. A longitudinally reciprocatory movement is thus imparted to the stylus with constant 50 variations in lengths of travel dependent

upon the variations in the surface of the film with which it coacts. A rack bar B³ is arranged to be reciprocated back and forth in accordance with the movements of the stylus. A simple arrangement is shown 55 diagrammatically wherein the rack bar B³ is yieldingly impelled endwise by a spring B⁵, into bearing relation against the spring or member B'. Meshing with the rack B³, is a pinion B⁴, carried upon a shaft B²⁰, 60 which pinion and shaft are thus rotatively moved through arcs of greater or smaller extents according to the range of movements of the stylus and rack bar, which, in turn, is governed by the character of surface of the film over which the stylus operates.

Mounted upon to turn with shaft B²⁰, are the disks B⁶, B⁷, which are of non-conducting material except for the segments or portions B¹⁴, B¹⁵, thereof which are of predetermined areas, and are in electric connection with the shaft B²⁰. Of course, if desirable, the pinion B⁴, and rack bar B³, may be electrically insulated from shaft B²⁰. The shaft 70 B²⁰ is in electrical connection through wire 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770

As will be obvious the disks B⁶, B⁷, may have any suitable relation, arrangement or structure, the important feature being that the conducting segments or portions B¹⁴, B¹⁵, shall retain their positions relative to each other, as indicated in the diagram of Fig. 2, a rotative displacement of the one conductor segment through any given extent being accompanied by a similar displacement of the other through exactly the same extent. Likewise it is essential that the several contacts shall operate in pairs, B⁸, with B¹¹, B⁹ with

B^{12} , and B^{10} with B^{13} , and that the one set B^8 , B^9 , B^{10} , be normally in circuit contact with their associated conductor segment B^{15} , while the other set is normally out of circuit contact with their conductor segment B^{14} . With these conditions obtaining it is quite immaterial what the structure or arrangement of the disks B^6 , B^7 , may be.

The operation of this part of the apparatus is as follows: The stylus B , following the inequalities of the surface of the film 10, on cylinder A, causes the rack bar B^3 , to shift back and forth endwise, thereby rotatively moving pinion B^4 , the shaft B^{20} , and the conductor segment carriers B^6 , B^7 , to a proportional extent. The rotation of the members B^6 , B^7 , from the normal positions thereof indicated in the diagram of Fig. 2, will be clockwise in the direction indicated by the arrows, the rack bar B^3 moving outward or away from the cylinder A. When the conductor segments, or their carriers, are thus rotatively moved through a sufficient angular distance determined by the character of the surface of the film over which the stylus operates, the contact B^8 , passes out of contact with conductor segment B^{15} , and contact B^{11} , passes into contact with segment B^{14} . This point, again is determined also by the adjustment of the contacts B^8 , B^{11} , with relation to the lowest point of elevation of the film surface. In the progress of the rack bar as determined by the passage of the stylus from this point of minimum height of the film surface to the point of maximum height of such surface, the three contacts B^{11} , B^{12} , B^{13} , are brought in successive order into contact with the segment B^{14} , while the contacts B^8 , B^9 , B^{10} , are carried, successively out of contact with segment B^{15} . The reverse movement of the rack bar secures the same sequential order of make and break of the circuits controlled by the several spring contacts.

I will now explain the action which takes place when the circuit make and break operations just described are accomplished, particular reference being had to Figs. 3 and 4.

The spring contacts B^{11} , B^{12} , B^{13} , are respectively included in circuit through the wires 32, 33, 34, with relay magnets C' , C^2 , C^3 , and the contacts B^8 , B^9 , B^{10} , are likewise included, respectively, in circuit through wires 35, 36, 37, with relay magnets C^4 , C^5 , C^6 . The respective relay magnets of these sets are arranged in coöperating pairs C' , C^4 , C^2 , C^5 ; and C^3 , C^6 ; as shown, the circuit of one member of each pair being broken at the same time that of the other member is completed through the action of the conductor segments B^{14} , B^{15} , and their coöperating spring contacts, as above described. The parts are shown in diagram in Fig. 3, as occupying their normal position with no ac-

tivity taking place, and the stylus at a point of minimum height in the film surface.

Associated with the respective pairs of relay magnets are members C^7 , C^8 , C^9 , each arranged to be moved in one direction or the other when one or the other of its associated pair of magnets is energized. Thus the member C^7 is moved into position to make contact with the terminal C^{10} , when the magnet C' is energized, and to make contact with terminal C^{11} , when magnet C^4 is energized, the movable armatures C^{16} , C^{19} , of said magnets operating when said magnets are respectively energized, to effect the movements of the said member C^7 . This member C^7 is in electrical connection through wire 38, with the other pole or side of the current source X, from that which is connected to the shaft B^{20} , or conductor segments B^{14} , B^{15} . Similarly, the member C^8 , is moved in one direction or the other by the armatures C^{17} , C^{20} , of magnets C^2 , C^5 , respectively, so as to contact with the terminals C^{12} , C^{13} , as the case may be. The member C^9 , is in electrical connection through wire 39, with terminal C^{10} . The member C^9 , in like manner is moved in one direction or the other to make contact with terminals C^{14} , C^{15} , as the case may be, by the armatures C^{18} , C^{21} , of magnets C^3 , C^6 , respectively. This member C^9 , is in electrical connection through wire 40, with terminal C^{12} .

In the operation of the apparatus for transmission, when the circuit connection between contact B^{11} , and segment B^{14} , is completed and that between the coöperating contact B^8 and segment B^{15} is broken, as above explained, the circuit of magnet C' is completed as follows: from battery or other current source X, through wire 31, segment B^{14} , contact B^{11} , wire 32, magnet C' , wire 41, terminal C^{11} , member C^7 , wire 38 to the opposite side or pole of the battery. In order that this circuit may be closed two conditions must concur, namely, the contact C^{11} must bear on segment B^{14} , and the member C^7 , must be in contact with terminal C^{11} . At the same time the circuit of magnet C' is closed the circuit of magnet C^4 is opened at B^8 , B^{15} . This circuit, when closed may be traced as follows:—from battery X, wire 31, segment B^{15} , contact B^8 , wire 35, magnet C^4 , wire 42, wire 43, terminal C^{13} , member C^8 , wire 39, terminal C^{10} , member C^7 , and wire 38, and return to battery. In order that this circuit may be closed the contact B^8 must bear on segment B^{15} and contact members C^8 and C^7 must be in position to contact respectively with terminals C^{13} and C^{10} . The closing of the circuit of magnet C' causes said magnet to become energized thereby attracting its armature C^{16} , and hence moving member C^7 away from terminal C^{11} , and into contact with terminal

C¹⁰. This action causes the circuit of magnet C' to be opened at the terminal C¹¹, and this circuit cannot be re-established until after contact B⁸ again contacts with segment B¹⁵, that is, until magnet C⁴ has again been energized so as to attract its armature C¹⁹, and again move member C', into contact with terminal C¹¹. When the member C' is moved into contact with terminal C¹⁰, as above explained, by the energization of magnet C', the conditions are established for completing the circuit of magnet C², as soon as the contact B¹² is brought into contact with segment B¹⁴. This occurs at the same time contact B⁹ leaves segment B¹⁵. When contact B¹² contacts with segment B¹⁴, under the conditions as explained, the circuit of magnet C² is completed as follows:—from battery X, through wire 31, segment B¹⁴, contact B¹², wire 33, magnet C², wire 44, wire 43, terminal C¹⁸, member C⁸, wire 39, terminal C¹⁰, member C', wire 38, and return to battery. The circuit of magnet C⁴ would be closed at the same time were it not for the fact that said circuit, at this stage is opened between contact B⁸ and segment B¹⁵. The apparatus is therefore, at this stage ready to respond to the action of magnet C², by the rotative displacement of the segment B¹⁴, in one direction, or to the action of magnet C⁴ by the rotative displacement of segment B¹⁵, in the opposite direction, that is, whether the stylus passes to a raised or to a depressed portion of the film surface. In the former case the magnet C² will be energized and in the latter case magnet C⁴ will be energized, and in the latter event the apparatus is restored to normal.

If the magnet C² is energized the resulting attraction of its armature C¹⁷ will cause member C⁸ to move into contact with terminal C¹² and out of contact with terminal C¹³. This puts the apparatus in condition for a further rotation of the segments B¹⁴, B¹⁵, in either a forward or a reverse direction, that is, into condition for the stylus to move over either a higher or a lower elevation of the film surface. If it be a higher elevation then contact B¹³, is brought into contact with the segment B¹⁴, and B¹⁰ is carried out of contact with segment B¹⁵. This action completes circuit through magnet C³ as follows: from battery X, wire 31, segment B¹⁴, contact B¹³, wire 34, magnet C³, wire 45, wire 46, terminal C¹⁵, member C⁹, wire 40, terminal C¹², member C⁸, wire 39, terminal C¹⁰, member C', wire 38 and return to battery. The completion of this circuit would also complete the circuit of magnet C¹, through wires 36, 47, 46, and on as just traced, were it not for the fact that said circuit, under the conditions named is open between contact B⁹ and segment B¹⁵. It will be seen that this circuit is completed only when contact B¹³ is on segment B¹⁴, and also, only after a previous energization of magnets C⁶, C², and C'. The completion of the circuit of magnet C³, causes the armature C¹⁸ thereof to be attracted, thereby moving member C⁹, out of contact with terminal C¹¹, and into contact with terminal C¹⁴. This places the apparatus in condition for the first step backward in the reverse direction, the maximum height of the film surface having been attained when circuit connection between contact B¹³, and segment B¹⁴ was established. The first reverse step after the maximum is reached brings contact B¹⁰, again into contact with the segment B¹⁵, thereupon completing the circuit of magnet C⁶, as follows: from battery X, through wire 31, segment B¹⁵, contact B¹⁰, wire 37, magnet C⁶, terminal C¹⁴, member C⁹, and on to the return to battery through the path last traced. The closing of this circuit energizes magnet C⁶, thereby attracting its armature C²¹, and causing member C⁹ to move out of contact with terminal C¹⁴, and into contact with terminal C¹⁵. This breaks the circuit of magnet C¹⁸, but leaves the apparatus in condition either for a next succeeding forward movement which would bring contact B¹³, again into connection with segment B¹⁴, thereby again completing the circuit of magnet C³, with the resultant operations as above described, or for a next succeeding reverse movement which would again bring contact B⁹ into contact with segment B¹⁵, thereby again completing the circuit of magnet C⁶, with the resultant operations above described.

Thus it will be seen that the energization of each magnet of the series and which, for convenience of description I will refer to as transmitter relays, breaks its own circuit but leaves the apparatus in condition for further operation in either forward or reverse direction, but that throughout the operation a fixed sequential order of operation is secured and maintained whether in forward or reverse operation, and no two magnets can be energized at the same time, the magnets C', C², C³, being energized successively in the forward operation of the apparatus, that is when the stylus passes from, say, a minimum to a maximum height on the film surface, while the relays C⁶, C⁵, C⁴, are energized in successive order when the stylus passes in reverse direction from a maximum to a minimum height of the film surface. But at each step whether forwardly or in reverse, the apparatus is left in condition to respond to either a forward or a reverse movement of the stylus.

The magnets C', C², C³, C⁶, C⁵, C⁴, control the impulses which are sent to the line and which operate the receiving apparatus in suitable and corresponding manner to be 130

hereinafter described, to reproduce in the same sequential order the maximum intermediate and minimum colors or shades of the photograph which is being transmitted.

5 The impulse control operation of these magnets is diagrammatically illustrated in Fig. 4.

In accomplishing the function of controlling the line impulses the armature of each 10 of the transmitter relays, when attracted by the energization of its associated magnet, completes a circuit connection from the local current source or battery to the line, thereby sending a current impulse to line 15 when the transmitter relay magnet is energized, and, in accordance with my invention, and according to the sequential order of operation of the transmitter relays, as determined by the successive sequence of colors 20 or shades in the photograph to be transmitted, as above described, these impulses are also sent to line in corresponding sequential order depending upon the sequence of shades or colors of the photograph. Also, in accordance 25 with my invention, I propose to so adjust and regulate the circuit connections employed in sending out the line impulses, in transmitting, as to control the time duration of each impulse, and, if desired, and preferably, to relatively vary the 30 duration of the impulses sent to line by the operation of the transmitter stylus in one direction, as compared with that of the impulses sent to line by the operation of the stylus in the other direction. In other words, and for illustration, as the stylus passes successively from a minimum to or 35 toward a maximum height of film surface I propose, in accordance with my invention, to send to line correspondingly successive 40 short impulses, say, of the order of transmitted "dots" of the ordinary telegraph operation, and when the stylus operates in reverse direction, that is, from a maximum to or toward a minimum height of the film surface, I propose to send successive corresponding 45 impulses of longer duration, say of the order of "dashes" in the ordinary telegraph operation.

50 An illustrative arrangement for accomplishing these results is shown in Fig. 4, wherein the relay armatures are respectively employed to effect the desired line connections. But since the operation of these 55 armatures is dependent upon the sequential order of operation of the stylus as determined by the various shades or colors of the photograph it will be seen that the line impulses also will be controlled and sent out 60 in correspondingly sequential order.

In the form shown as illustrative of the principles of my invention the armatures C^{16} , C^{17} , C^{18} , C^{19} , C^{20} , C^{21} , respectively carry the arms C^{22} , C^{23} , C^{24} , C^{25} , C^{26} , C^{27} , said 65 arms respectively co-operating with conduct-

ing members C^{28} , C^{29} , C^{30} , C^{31} , C^{32} , C^{33} . In practice the conductor members referred to should be of such structure and relation, and suitably mounted for adjustment so that the duration of the impulses sent to line as well as the exact instant of commencement thereof, may be accurately controlled and determined. As shown, the conductor members are of tapering formation, the contact arms moving transversely thereacross, thereby contributing to the control of the duration and point of commencement of the impulse to be sent to the line. These conductor members are connected to the line, and for the purpose of adjustment each set is mounted on a carrier C^{34} , with which 75 engages an adjusting screw C^{35} . In order to secure an increased duration of the impulses sent to line by the magnet relays C^4 , C^5 , C^6 , the conductor members C^{31} , C^{32} , C^{33} , 80 C^{25} , C^{26} , are preferably of greater relative transverse widths than that of the members C^{28} , C^{29} , C^{30} .

The armature of each of the impulse controlling relays is suitably connected to one 90 side or pole of battery X . Thus, armature C^{16} , is connected through wire 41 to terminal C^{11} , and thence to battery through member C^7 , and wire 38, when said member C^7 has been moved into contact with said terminal. The armature C^{19} is connected through wire 48, to terminal C^{10} , and thence to battery through member C^7 and wire 38 when said member C^7 is moved into contact with said terminal C^{10} . In like manner armature C^{17} is connected through wires 49, 44, and 43 to terminal C^{13} , and thence on to battery; the armature C^{20} , through wires 50 and 40 to terminal C^{12} , and on to battery; armature C^{18} , through wires 51, 45, 100 and 46, to terminal C^{15} , and on to battery; and armature C^{21} , through wires 52 to terminal C^{14} , and on to the battery, all as before explained in connection with the circuits of the relay magnets themselves. Thus 110 it will be seen that the same sequential order as before is maintained in the impulses sent to line as in the case of the operation of the relay magnets, this order being controlled as before explained by the movements of the stylus as determined by the configuration of the film surface over which it operates. It will also be seen that whenever the circuit of any relay magnet is opened, the impulse circuit controlled by 115 its associated armature is likewise opened.

From the foregoing description it will be evident that when the stylus passes consecutively through the complete distance from a minimum height to a maximum height in 125 the surface of the film three "dot" impulses are successively sent to the line, and when said stylus passes consecutively through the complete reverse distance, that is from a maximum to a minimum height of film sur- 130

face three "dash" impulses are sent to line. The line impulses "dots" and "dashes", above explained, are employed at the receiving end to control suitable photographic reproducing devices. These devices may be of any desired character. In its essential characteristic the receiver embodies a step by step mechanism which progressively varies the area of opening of apertures for admitting more or less light into a camera which is arranged in suitable relation with respect to a photographic film which is actuated or moved in synchronism with the cameo-film at the transmitting station. If a positive pictures is employed at the transmitter, the "normal" condition of the light chamber at the receiving end should be that of complete closure of the shutter. This would leave the film unaffected by light, thereby printing black on the receiver film and producing a true negative. If a negative is employed at the transmitter this arrangement would give a true positive picture at the receiver. The production of a negative at the receiver would of course require a normal complete opening of the camera shutter at the beginning of the receiving operation. In the case of the negative therefore, the sequence would be black, dark, gray, light gray, white, while in the case of the positive this sequence would be just the reverse.

In Fig. 5 I have shown, diagrammatically an illustrative arrangement of step-by-step mechanism for operating the shutter of the receiving camera. The polarized relay magnet R which is shown and referred to in connection with the description of Fig. 1, is energized by the impulses which come in over the line wire from the distant transmitting station, and which are inaugurated and controlled as I have already explained. When the magnet R is energized by a received impulse it attracts its armature R¹⁰, which is thereby brought into contact with terminal R'. This action completes the following circuit: from local current source X', through wire 53, armature R¹⁰, terminal R', wire 54, magnet R², wire 55, to the other side of the current source X'. If the received impulse is a short one, that is, if it is of the character of a "dot," the resulting operation is as follows: The magnet R², which is preferably of the solenoid hollow core and plunger armature type, when thus energized, exerts a quick pull upon its core R²¹, to which is connected an arm R²². Upon this arm is pivotally mounted a pawl R¹⁸. As the arm R²², moves toward the magnet R², the pawl R¹⁸, thereon engages the nearest juxtaposed tooth of a ratchet wheel R¹³, mounted upon a suitable shaft R²³, thereby rotatively displacing said ratchet wheel and shaft through an angular distance sufficient to allow the pawl R¹⁸

to clear and pass on beyond the tooth with which it engaged. This movement of arm R²², is against the action of a suitable retractile R²⁴, which serves to return said arm to its normal position the instant the current impulse ceases. By reason of being pivoted the pawl R¹⁸ is enabled to swing loosely and idly over the ratchet teeth on wheel R¹³, during the retracting movement of arm R²². The immediate effect of rotating the ratchet R¹³, and shaft R²³, through the specified angular distance is to rotate a roller or wheel R¹⁷, which is also mounted on or driven from the same shaft R²³, through the same angular distance, thereby bringing a conductor segment R⁷, carried thereby, into electrical connection with a contact R²⁰. The segment R⁷ is in electrical connection with one pole of the station battery X', and therefore the following circuit is completed: from battery X', through wire 53, wire 56, wire 57, shaft R²³, segment R⁷, contact R²⁰, wire 58, magnet R⁵, wire 59, terminal R³, arm R¹⁸, wire 60 to the other pole of the battery. The arm R¹⁸, is normally held in contact with terminal R³, as, for instance, by means of a spring R²⁵. The arm R²², however, as it approaches the limit of its ratchet actuating throw engages the arm R¹⁸, and moves it away from terminal R³, and into contact with a terminal R⁴, said arm R¹⁸ being restored to its normal position in contact with terminal R³, only after the arm R²², has moved through a predetermined distance in its return movement. Consequently the circuit of magnet R⁵ is not completed until after magnet R² has ceased to act. The magnet R⁵ is of the same type as R², and to the core R²⁶ thereof is connected an arm R²⁷, which carries a pivoted pawl R¹⁵, arranged to operate in connection with the teeth of a ratchet wheel R¹², also mounted on shaft R²³. The movement of the arm R²⁷ and core R²⁶, when magnet R⁵, is energized is opposed by a spring R²⁸. The energization of magnet R⁵, therefore, causes another step of rotative displacement to be imparted to shaft R²³, in the same manner as before described in connection with ratchet wheel R¹³. This second step of rotation imparted to shaft R²³, causes the segment carrier R¹⁷ to rotate into position to carry the contact R²⁰, off of conductor segment R⁷, and on to an insulated surface of said carrier. This opens the circuit of magnet R⁵, thereby causing the arm R²⁷, to return to its normal position, the pivoted pawl R¹⁵, wiping loosely past the teeth of ratchet R¹².

The cycle of operation just described, namely, the momentary energization of magnets R² and R⁵ in succession with the resultant rotative actuations of shaft R²³, is accomplished as a result of a single impulse or "dot" received over the line. A second

impulse or "dot" received over the line repeats this same cycle of operation, the magnet R^2 , first operating to rotatively move the shaft R^{23} , to cause the conductor segment R^8 to be brought into electrical contact with contact R^{20} , thereby again closing the circuit of magnet R^8 and hence imparting still another step of rotative movement of shaft R^{23} , to cause the contact R^{20} , 10 to be carried off of conductor segment R^8 , and onto an insulating part of wheel or carrier R^{17} , to restore the parts to their rest positions. In like manner a third impulse or "dot" received over the line will cause 15 the conductor segment R^8 to be brought into contact with contact R^{20} , and then carried on beyond said contact.

The step-by-step rotative movements imparted to shaft R^{23} , are utilized to operate 20 the camera mechanism, and it will be observed that the camera shutter is thus actuated twice for each received impulse. The camera shutter to be actuated may have many specifically different forms. For the 25 purpose of illustrating an operative embodiment of my invention I have shown, in diagram, in Fig. 6, a form of rotative disk shutter G , having a succession of openings G' , G^2 , G^3 , of relatively increasing areas. 30 These openings are arc-shaped concentric with the shaft or axis about which the disk rotatively moves. This may be shaft R^{23} , as shown, or, as is obvious, it may be a shaft driven from shaft R^{23} . Such a disk shutter 35 is of convenient and appropriate form for use in controlling access of light to the camera at the receiving station. This disk is to be placed in front of a suitable photographic light chamber in the wall of which 40 is an aperture Z through which light is admitted to said chamber when an opening G' , G^2 , or G^3 , is brought into line therewith, the quantity of light admitted being dependent upon the area of said opening G' , 45 G^2 , or G^3 . In order to bring the said openings successively into register with the aperture in the light chamber, the disk G , is rotatively moved from left to right as indicated by the arrow. In the drawing the 50 disk G is shown in its neutral position before the receipt of any impulse from the transmitting station, and with the radial line 1 in vertical position. Assuming that at each actuation of either of the magnets 55 R^2 or R^5 , the shutter disk G is rotatively moved through an arc of 20 degrees, the first impulse received acts, as above explained, to successively energize the magnets R^2 and R^5 , and then both said magnets 60 and associated parts are restored to their normal or rest positions. The actuation of magnet R^2 causes the radial line 2 to be brought into vertical position. This, however, does not open the aperture Z to admit 65 light to the camera chamber, and conse-

quently the receiving film surface corresponding to this position of the shutter will be dark. The immediately succeeding actuation of magnet R^5 , causes the radial shutter line 3 to be brought into vertical position thereby bringing the opening G' into register with the aperture Z , and admitting sufficient light to the camera chamber to produce a dark gray on the receiver film or print. The second impulse received brings 70 the radial line 4 into vertical position when magnet R^2 is energized, which does not alter the amount of the light admitted to the camera chamber since the aperture Z still remains in register with the opening G' . 75 But the immediately succeeding energization of magnet R^5 , brings the enlarged opening G^2 into register with the apertures, with the radial line 5, in vertical position, thereby admitting more light to the camera chamber 80 and producing a light gray effect on the receiving film. The third impulse received over the line operates, in like manner, to first bring the radial line 6 into vertical position, which does not affect any change in 85 the light admitted, and then to bring the radial line 7, into vertical position which brings the opening G^3 into register with the aperture Z and admits the maximum of light to the camera chamber, thereby 90 producing the effect of white on the receiving film. This completes the cycle of operation and I have described the action which takes place when three successive short or 95 "dot" impulses are sent and received, 100 these, as above explained, corresponding to the continuously successive movements of the transmitting stylus from a minimum to a maximum height of surface on the transmitting relief-film. That is, the operation 105 passes successively through the sequence of stages required to reproduce a succession of colors or shades of the picture, say, from dark to light through the intermediate stages of dark gray and light gray. 110

If however, at any point in the forward cycle of operation above described, it is necessary to reverse the process, that is, if, instead of the transmitting stylus progressing continuously from a minimum to a 115 maximum height on the relief film at the transmitting station, it is required to pass at some intermediate point from a higher to a lower elevation on said film, the impulses sent to the line are of longer duration—theoretically twice as long—as those sent to line by the forward cycle. These impulses, as above explained are of the order of "dashes." The duration of the "dash" impulses is of course to be determined by operating conditions and is controlled by suitable adjustments. These impulses affect the apparatus as follows: The first "dash" impulse energizes the line relay magnet R , as before, causing its armature 125 130

R¹⁰ to be attracted against terminal R', thereby closing the circuit of magnet R², as before. The resulting energization of this magnet causes arm R²² to be moved, thereby 5 rotatively actuating shaft R²³, through one step in the same direction as before. At the same time, however, the member R¹⁸ is moved against terminal R⁴. This action 10 closes the following circuit: from battery X', through wire 53, wire 56, wire 61, magnet R⁶, wire 62, terminal R⁴, member R¹⁸, wire 60 to the other pole of the battery. This same circuit is closed each time magnet R² is energized, but the winding of magnet 15 R⁶ is such that when a dot impulse is sent the closing of this circuit last traced does not affect said magnet R⁶. This result of failing to energize the magnet R⁶, except when a "dash" impulse is sent or a continued contact of R¹⁰ with R', for a sufficient 20 interval of time is maintained may be accomplished in any other suitable manner well known to persons skilled in the art, the momentary contact of R¹⁰, with R', when magnet R is energized by a short or "dot" 25 impulse, not being sufficient to cause magnet R⁶ to be sufficiently energized. When therefore a "dash" impulse is operating, its duration being greater than that of the 30 "dot" impulse before described, the member R¹⁸ is held against terminal R⁴, a sufficient length of time to permit the magnet R⁶ to become sufficiently energized to cause it to accomplish its purpose. The plunger 35 R³⁰, of magnet R⁶, carries an arm R³¹, which is normally retracted by a spring R³², and carries a pivoted pawl R¹⁴, which operates with a ratchet R¹¹, on shaft R²³. The arrangement and relation of arm R³¹, 40 pawl R¹⁴, and ratchet R¹¹, relatively to the shaft R²³, is such that when the magnet R⁶ is sufficiently energized, the shaft R²³ is rotatively moved in reverse direction to that in which it is actuated by the ratchets 45 R¹², R¹³.

It will be remembered that at each "dot" impulse sent to line the shaft R²³ is given two steps of rotative movement forwardly, one due to the energization of magnet R² and one to that of magnet R⁶. It will also be remembered that when a "dash" impulse is sent to line the first action is to impart another step of rotative movement forwardly to shaft R²³ by reason of the resulting energization of magnet R⁶. Therefore, if a "dot" impulse sent to line is immediately followed by a "dash" impulse, in order to sufficiently displace the shaft R²³, rotatively, in the reverse direction to 50 pass from one color or shade of the picture to the next in the sequential order thereof, it is necessary to secure from each energization of magnet R⁶, a reverse rotative movement of shaft R²³, and hence of the 55 shutter G, through a distance correspond-

ing to three forward steps of displacement thereof. This result may be secured in any suitable or convenient manner through suitable reduction gear connections between ratchet R¹¹, and shaft R²³. As illustrative 70 of the principles involved I have shown the ratchet R¹¹, of approximately one third the diameter of ratchets R¹², R¹³, and consequently when moved by the energization of magnet R⁶, the shaft R²³ is displaced to an 75 extent three times greater than when displaced by the actuation of either magnet R² or R⁶. Three successive longer or "dash" impulses sent to line, as would be the case if the transmitting stylus passed 80 in successive order continuously from a maximum to a minimum height on the relief film, would thus rotatively displace the camera shutter through an angular distance equivalent to that of nine shorter or "dot" 85 impulses, namely, the six forward steps due to three "dot" impulses, as above explained, and three additional forward steps effected as initially incidental to the three "dash" impulses. 90

It is for the purpose of accommodating the additional forward step of rotation of the camera shutter as an initial incident to each "dash" impulse without interfering with or varying the amount of light admitted to the receiving camera by reason of such additional forward step that each opening G', G², G³, of the shutter is elongated to an extent corresponding to two steps of rotative movement of the shutter. 100 By such arrangement and relation of openings in the shutter I avoid the possibility of even momentarily admitting light through, say, the second or the third opening when it is desired to reverse from the first to the 105 minimum, or from the second to the first stages, and which would be destructive of practical successful photographic transmission.

It will, of course, be understood that the 110 receiving film will correspond in relative arrangement and relation, to the transmitting film. That is to say, where the transmitting film is operated in cylindrical form, the receiving film is likewise of cylindrical form. 115 In this case the receiving film will be revolved axially and moved endwise in exact synchronism with the transmitting film, the synchronizing arrangement hereinabove described to secure these results. 120

It is believed that the operation of the system will be fully understood from the foregoing description taken in connection with the accompanying drawings, and briefly is as follows:— 125

A transmitting film is suitably prepared from a picture to be transmitted, and a sensitized receiving photographic film is arranged at the receiving station to receive the transmitted picture. These films are oper- 130

ated in synchronism. A tracing stylus operates over the transmitting film, and the movements imparted thereto by following the irregular surface of said film are employed to send current impulses to line, the impulses due to the movement of the stylus in one direction being of shorter duration than those due to the movement of said stylus in the opposite direction. The 10 movements of the stylus in either direction are in accordance with a fixed invariable sequence of shades of the picture to be transmitted. The impulses thus sent to line are utilized at the receiving station to correspondingly operate a camera shutter at that station which controls the action of a camera upon the receiving film.

It is to be understood that in the broadest scope of my invention as defined in the 20 claims I am not to be limited or restricted to the specific details of structure arrangement and operation shown and described, as variations therefrom and changes therein throughout a wide range would readily occur 25 to persons skilled in the art, and still fall within the spirit and scope of my invention.

But what I claim as new and useful, and of my own invention, and desire to secure by Letters Patent, is,—

30 1. In an apparatus of the character described, a line circuit and means to send current impulses to the line circuit, in combination with means to maintain the sequential order of the impulses in accordance with 35 the successive shades or colors to or from one extreme or the other of the photograph or picture to be transmitted, each impulse operating to leave the apparatus in condition for the action of the next succeeding 40 impulse whether it corresponds to a shade or color toward or away from either extreme, the impulses corresponding to the progressive shades from one extreme being of equal value and those corresponding to the 45 progressive shades from the other extreme being of equal value and of relative shorter duration than, said first mentioned impulses.

2. In an apparatus of the class described, a line circuit, a source of current, contacts 50 to control the circuit connections of the current source to the line, said contacts arranged in sets, one set corresponding to the progressive shades from maximum to minimum of a photograph or picture to be transmitted, and the other set corresponding to the said shades from minimum to maximum, and means controlled in accordance with said shades and in the sequential order thereof for closing said contacts in succession.

60 3. In an apparatus of the class described, a line circuit, a source of current, contacts to control the circuit connections of the current source to the line, said contacts arranged in sets, one set corresponding to the 65 progressive shades from maximum to mini-

mum of a photograph or picture to be transmitted, and the other set corresponding to the said shades from minimum to maximum, the duration of closure of one set of contacts exceeding that of the other set, and means controlled in accordance with said shades and in the sequential order thereof for closing said contacts.

4. In an apparatus of the class described, a line circuit, a source of current, relays for closing the circuit connection of the current source to the line, said relays operating in sequential order corresponding to the progressive shades of a photograph or picture to be transmitted, the actuation of each relay operating to open its own circuit and to close contacts in the circuit of the next relay in the sequential order thereof, and means controlled in accordance with the said shades for controlling the circuits of said 85 relays.

5. In an apparatus of the class described, a line circuit, a source of current, relays arranged in sets and operating in sequential order to close the circuit connection of the 90 current source to line, and means controlled in accordance with the shades and lights of a photograph or picture to be transmitted for controlling the circuits of said relays in the progressive order of said shades and 95 lights.

6. In an apparatus of the class described, a line circuit, a source of current, relays arranged in sets and operating in sequential order to close the circuit connection of the 100 current source to line, the duration of closure of one set being greater than that of the other set, and means controlled in accordance with the shades and lights of a photograph or picture to be transmitted for 105 controlling the circuits of said relays in the progressive order of said shades and lights.

7. In an apparatus of the class described, a line circuit, a source of current, relays for closing the circuit connection of the current 110 source to line, means for adjusting the duration of the closure of said connections, and means controlled in accordance with the shades and lights of a photograph or picture, for controlling the circuits of said 115 relays in the sequential order of occurrence of said shades and lights in the photograph or picture.

8. In an apparatus of the class described, a line circuit, a source of current, relays for 120 closing the circuit connection of the current source to line, said relays arranged in sets, the relays of one set arranged to operate in the successive order of the shades of a photograph from minimum to maximum, and 125 those of the other set in the successive reverse order of said shades, and means for operating said relays in accordance with said shades.

9. In an apparatus of the class described, 130

a line circuit, a source of current, relays for closing the circuit connection of the current source to line, said relays arranged in sets, the relays of one set arranged to operate in the successive order of the shades of a photograph from minimum to maximum, and those of the other set in the successive reverse order of said shades, means for operating said relays in accordance with said 10 shades, and means whereby the actuation of any relay of either set places the next successive relay of the set in condition for operation.

10. In an apparatus of the class described, 15 a line circuit, a source of current, relays for closing the circuit connection of the current source to line, means for adjusting the duration of the closure of said connections, and means controlled in accordance with the 20 shades and lights of a photograph or picture, for controlling the circuits of said relays in the sequential order of occurrence of said shades and lights in the photograph or picture and means whereby the actuation of 25 a relay places the next successive relay in condition for actuation.

11. In an apparatus of the class described, means to impress current impulses upon the line in the successive sequential order of occurrence of shades in a photograph, whether such order is progressive from minimum to maximum or the reverse, and means controlled by said current impulses to control the size of a light aperture to duplicate said 35 shades in like order at the receiving station.

12. In an apparatus of the class described, a transmitting apparatus including means to send to line a series of current impulses in accordance with the successive sequential 40 order of occurrence of the shades in a photograph to be transmitted, in combination with a receiving apparatus including a sensitized film, and a camera shutter to expose the same to light, and step by step 45 operated devices actuated by the received impulses for opening said shutter to greater or less degree in correspondence with the shades of the photograph and in the same sequential order thereof.

50 13. The method which consists in transmitting current impulses to line in a fixed successive sequential order of occurrence of shades in a photograph whether such order is progressive from minimum toward maximum or the reverse, and utilizing said impulses to control the size of a light opening to thereby in like order effect the duplication of said shades at the receiving station.

14. The method which consists in transmitting "dot" and "dash" current impulses to line in the successive sequential order of occurrence of shades in a photograph, the "dot" impulses corresponding to the said shades in progressive order from minimum 65 toward maximum, and the "dash" impulses

corresponding to the said shades in reverse order, and utilizing said impulses to control in like order the duplication of said shades at the receiving station.

15. The method which consists in transmitting current impulses to line in a fixed successive sequential order of occurrence of shades in a photograph, whether such order is progressive from minimum toward maximum, or the reverse, and utilizing said impulses to control in like order the size of exposure to corresponding degrees of light of a receiving sensitized film. 70

16. The method which consists in transmitting current impulses to line in a fixed 80 successive order corresponding to the fixed rotation of shades in a photograph or picture from minimum toward maximum or the reverse, and utilizing said impulses to control, in like order, the corresponding degrees of the size of exposure of a sensitized film to light at the receiving station. 85

17. In an apparatus of the class described, a line circuit, and means to send current impulses of uniform intensity to line in a 90 fixed sequential order corresponding to the occurrence of shades in a photograph, in combination with means at the receiving end of the line controlled by said current impulses to control the size of a light aperture to duplicate the shades of said photograph in like order. 95

18. In an apparatus of the class described, a line circuit, and means to send current impulses of uniform intensity to line in a 100 fixed sequential order corresponding to the occurrence of shades in a photograph, in combination with a sensitized receiving film at the receiving station, and means controlled by said line impulses to control the 105 size of a light aperture for duplicating the shades of the photograph in like order on said film.

19. In an apparatus of the class described, a line circuit and means to send current impulses thereover in a fixed sequential order corresponding to the occurrence of shades in a photograph, said impulses being of uniform intensity but varying in duration according to whether the successive shades 110 progress from minimum toward maximum or the reverse, in combination with a sensitized film at the receiving station, and means controlled by said line impulses to control the size of a light aperture for duplicating said shades, in like order, on said film. 115

20. In an apparatus of the class described, a line circuit and means to send current impulses thereover in a fixed sequential order 120 corresponding to the occurrence of shades in a photograph, in combination with a sensitized film at the receiving station, a shutter for exposing the same to light, said shutter having an opening therethrough of rel. 130

atively increased area corresponding to the photographic shades, and means controlled by said line impulses for correspondingly operating said shutter.

- 5 21. In an apparatus of the class described, a line circuit and means to send current impulses thereover in the sequential order corresponding to the occurrence of shades in a photograph, in combination with a sensitized receiving film, a step by step mechanism for exposing the same to light in varying degree corresponding to the photographic shades, each received impulse operating to actuate said mechanism through
- 10 15 two steps.

22. In an apparatus of the class described, a line circuit, and means to send current impulses thereover in the sequential order corresponding to the occurrence of shades in a photograph, in combination with a sensitized receiving film, a step by step mechanism for exposing the same to light in varying degree corresponding to the photographic shades, said impulses varying in duration according to whether the successive shades progress from minimum to maximum, or the reverse, the impulses operating said mechanism in one direction or the other according to the duration thereof.

- 30 23. In an apparatus of the class described, a line circuit, and means to send current impulses thereover in the sequential order corresponding to the occurrence of shades in a photograph, in combination with a sensitized receiving film, a shutter to control the exposure of the film to light, said shutter having an opening of progressively varying size corresponding to the photographic shades, said impulses varying in duration according as the photographic shades progress from minimum toward maximum, or the reverse, each impulse of one duration operating to actuate said shutter in one direction and each impulse of longer duration operating to actuate it in the other direction.

24. In an apparatus of the class described, a line circuit, and means to send current im-

pulses thereover in the sequential order corresponding to the occurrence of shades in a photograph, in combination with a sensitized receiving film, a shutter to control the exposure of the film to light, said shutter having an opening of progressively varying size corresponding to the photographic shades, said impulses varying in duration according as the photographic shades progress from minimum toward maximum, or the reverse, each impulse of one duration operating to actuate said shutter through 60 two steps in one direction, and each impulse of longer duration operating to actuate it through one step in the same direction and three steps in the reverse direction.

25. In an apparatus for transmitting photographs, pictures or the like telegraphically, a line circuit, a transmitting machine and a receiving machine, means for operating said receiving machine in one direction in accordance with electrical impulses of equal duration to line from said transmitting machine, and means for reversing the operation of said receiving machine in accordance with electrical impulses of greater duration to line from said transmitting machine.

26. In an apparatus for transmitting photographs, pictures or the like telegraphically, a line circuit, a transmitting machine and a receiving machine, means for operating said receiving machine in one direction through a fixed sequence of steps in accordance with electrical impulses to line from said transmitting machine, and means for reversing said receiving machine through 85 the reverse of said fixed sequence of steps, in accordance with the shades of the photograph to be transmitted.

In testimony whereof I have hereunto set my hand in the presence of the subscribing 90 witnesses, on this 3rd day of June A. D., 1915.

JAMES E. HOMANS.

Witnesses:

A. B. THOMAS,
S. E. DARBY.
